UNITED STATES PATENT OFFICE.

WILBER L. MILLER, OF WASHINGTON, IOWA.

VEIN-DILATOR FOR EMBALMERS' USE.

SPECIFICATION forming part of Letters Patent No. 668,879, dated February 26, 1901.

Application filed July 19, 1900. Serial No. 24,168. (No model.)

To all whom it may concern:

Be it known that I, WILBER L. MILLER, a citizen of the United States of America, and a resident of Washington, county of Washington, and State of Iowa, have invented certain new and useful Improvements in Vein-Dilators for Embalmers' Use, of which the following is a specification.

My present invention relates to an improvement in vein-dilators for the use of embalmers, the object of the same being to provide a simple, efficient, and inexpensive device having many attributes of novelty as an instrument for the use of embalmers in dilating the veins in such a manner as to admit a catheter; and the invention consequently consists, essentially, in the construction, combination, and arrangement of parts, substantially as will be hereinafter more fully described and claimed.

In the accompanying drawings, illustrating my invention, Figure 1 is a side elevation, in partial section, of my improved vein-dilator, the two principal parts of the instrument being shown as dissociated from each other. Fig. 2 is a similar side elevation showing the tubular portion of the device inserted part way into the distensible spring-pointed portion. Fig. 3 is a side elevation showing the tubular part inserted clear into the distensible part.

Similar numerals of reference designate corresponding parts throughout the different figures of the drawings.

In carrying my invention into practical effect I employ two principal parts, one of which is a small cylinder or tube having a uniform diameter throughout and the other is a short tube which is split or cut longitudinally for about two-thirds of its length so as to provide three spring-points, the integral tubular portion being adapted for insertion into the other in a manner and for a purpose to be presently stated.

1 denotes the part of the device consisting of an integral tube open at each end and of uniform diameter throughout, there being at one end a flange or collar 2, which serves as a handle. The other part of the device consists of a tube 3, of slightly-greater diameter than tube 1, so that it may easily be introduced

thereinto, said tube 3 for about two-thirds of its length being split or cut with slots, as at 4, to form spring prongs or points 5. These points 5, of which there are preferably three, are bent 55 toward the central axis of the tube 3, so that their outer tips may converge to a single point. The tube 3, with its spring-points 5 converging to a single point, is shown at the left in Fig. 1 and presents the appearance of a small instrument having a single sharp point which may be introduced into the vein.

In Fig. 2 I have represented the smaller tube 1 in the act of being introduced into the integral end of the split tube 3—that is to say, 65 that end of said tube which carries the collar or ring 6, which is similar to the collar 2—and it will be noticed that the farther the smaller tube 1 is pressed into the outer tube 3 the more the spring-points 5 will be separated 70 from each other or distended with their tips farther and farther apart. When the smaller tube 1 has been forced entirely into the outer tube 3, the inner and outer tube will occupy the relative positions shown in Fig. 3, where 75 it will be seen that the handle or collar 2 is against the handle 6, while the points of the spring-prongs 5 are separated as far from each other as it is possible to do with the insertion between them of the small tube 1.

It will thus be seen that I provide an instrument whereby a vein may be dilated to such proportions as to admit a catheter which is used for the purpose of withdrawing the blood, and that my device consists, essentially, of two metallic tubes—a larger and a smaller—the smaller being adapted for insertion into the larger for distending the spring-prongs of the latter. When the points of these prongs are together, the small point thus formed may be introduced into a vein, and then by pressing the inner tube into the outer tube the vein will be dilated, so that the catheter may be easily introduced into the vein through the opening of the inner tube, 90 thus enabling the heart to be reached with the catheter without tearing the vein.

Having thus described my invention, what I claim as new, and desire to secure by Letters Patent, is—

1. In a vein-dilator, the combination with a tube formed with converging spring-prongs,

and a tube of smaller diameter adapted to be inserted in the same to distend and hold said points.

2. In a vein-dilator, the combination with 5 a tube formed with converging spring-prongs, of a second tube of smaller diameter adapted to be inserted in the first-mentioned tube to distend and hold said prongs, and rings or

flanges formed on the outer end of said tubes to control and manipulate the same.

Signed at Washington, Iowa, this 12th day of July, 1900.

WILBER L. MILLER.
